UNITED STATES PATENT OFFICE.

OSCAR C. RIXSON, OF NEW ROCHELLE, NEW YORK.

DOOR CLOSER AND CHECK.

1,266,320.

Specification of Letters Patent. Patented May 14, 1918.

Application filed July 28, 1915. Serial No. 42,249.

To all whom it may concern:

Be it known that I, OSCAR C. RIXSON, a citizen of the United States, residing at New Rochelle, in the county of Westchester 5 and State of New York, have invented certain new and useful Improvements in Door Closers and Checks, of which the following is a full, clear, and exact description.

This invention relates to checks or to combined closers and checks for doors and the like, of the type which comprises a cup-shaped or cylindrical shaped casing which houses a spindle, cylinder, and a reciprocating piston which retards the movement of 10 the door by alternately drawing in and discharging a suitable liquid from its cylinder, upon rotation of the spindle. The invention has for its objects the provision of a 15 check or a closer and check of this character which is of a simple and compact construction, which is positive in its operation, and which may be cheaply and economically manufactured.

Accordingly, the invention contemplates 20 arranging the cylinder and spindle in parallelism within the casing and connecting these parts so that they will rotate together, the cylinder virtually forming an extension of the spindle. Suitable clutch members 25 are also preferably provided, which coöperate with stops on the spindle and cylinder as well as stationary abutments on the casing, so that upon the rotation of the spindle and cylinder in either direction the 30 spring will be wound up and placed under tension. The piston within the cylinder is preferably constructed to rotate with the cylinder and is reciprocated by suitable linkage mechanism upon rotation of the spindle and cylinder in either direction.

The invention also contemplates the combinations and constructions which will be hereinafter set forth in the specification and particularly pointed out in the appended 45 claims.

In the accompanying drawings:

Figure 1 shows in elevation my improved form of door closer and check showing a portion of a door and door casing;

Fig. 2 is a plan view of the same;

Fig. 3 is a central longitudinal section through the casing and the actuating parts of the door closer and check inclosed therein;

Fig. 4 is a plan of Fig. 3, with the top 55 or cover of the casing removed;

Fig. 5 is a sectional view on the line 5—5 of Fig. 3, looking downwardly;

Fig. 6 is a detail view on an enlarged scale of the lower clutch member; 60

Fig. 7 is a perspective view of the upper clutch member;

Fig. 8 is a detail showing in elevation the upper clutch member and its associated parts; and 65

Fig. 9 is a detail of the cam groove and the follower block.

Referring first to Figs. 1 and 2, a portion of a door casing is shown and designated 1, which surrounds a swinging door 2, which is 70 secured to the casing as by the hinges 3. The door closer and check is secured to the door and door casing preferably adjacent the inner upper end of the door, and comprises a substantially cylindrical or cup-shaped casing 4, having integral legs or plates 5 extending laterally therefrom, which rest against the door and are secured thereto by the screws 6. The cup-shaped casing is provided with a cover 7 held in place by screws 80 7'. Projecting through the cover is a spindle having a squared end 8 upon which is mounted a crank arm 9'. Secured to the other end of the crank arm is an extensible link 10' which is connected to a short link 85 12' having a pivoted bearing in a plate 13' carried by the door casing, the general construction thus far described, being similar to the door check at present used.

As shown in Fig. 3, the cover 7 is provided with a centrally disposed upstanding boss, which forms a bearing for the cylindrical portion 9 of the spindle. The spindle which does not extend to the bottom of the casing has a cylindrically-shaped 95 lower end forming a disk 10 of a larger diameter than the other parts thereof over which is fitted the open end of a hollow cylinder 11. The cylinder 11 is preferably secured to the part 10 by forcing portions 100 of the cylinder into suitable recesses or apertures formed in the disk 10, which construction provides a rigid joint between these parts and constrains them to rotate together. The portion 12 of the spindle 105 intermediate the parts 9 and 10 is of a somewhat irregular shape being substantially rectangular in shape and has pro-

jecting laterally therefrom an arm or finger 13, the purpose of which will be later described. The cylinder 11 is closed at its lower end and is preferably made from tube 5 steel which requires no machining of the parts. Secured to the inner face of the bottom of the cylinder, is a disk 14 and to the outer face a disk 15, these parts being secured in place by rivets 16. The disk 14 10 is provided with a suitable valve opening upon which a ball 17 seats and a strap 18 prevents the ball 17 from being displaced. The bottom of the cylinder and the plate 15 are provided with apertures 17' alining 15 with the valve opening in the disk 14 whereby communication is established with the annular chamber 19 surrounding the cylinder 11. The disk 15 carries a downwardly projecting sleeve 15' which fits over 20 a centrally disposed cylindrically-shaped valve body or casing 20 which passes into the interior of the casing through a suitable centrally disposed opening in the bottom of the casing. Communicating with a chamber 21 in the valve body, is an orifice 21' leading from the interior of the cylinder 11. The size of this orifice is controlled by a needle valve 22 threaded into the valve body 20, which regulates the speed of dis- 25 placement of the liquid from the cylinder as will be later referred to. Laterally disposed outlets 24 connect the chamber 21 with the annular chamber 19 through suitable openings in the sleeve 15'. Mounted 30 upon the sleeve 15' is a clutch member 25, which will be later referred to, and which is similar to the sleeve 15', is provided with suitable recesses 26, communicating with the outlets 24 so that the liquid passing 35 through these outlets may have a free passage into the chamber 19.

Slidably mounted in the cylinder 11 is a piston 27. The chamber 19 is filled with a suitable liquid, as oil, to a level with the 45 lower end 10 of the spindle. It will therefore be seen that when the piston 27 moves upwardly, the vacuum created will cause the ball 17 to be lifted from its seat and the liquid within the chamber 19 will flow into 50 the cylinder. When the piston moves downwardly, the pressure upon the ball 17 will cause it to close and the liquid is forced through the orifice 21' into the chamber 21 in the valve body 20, from which it 55 again flows into the chamber 19 through the outlets 24 and recesses 26 in the clutch member 25. By adjusting the size of the orifice which is controlled by the needle valve 22, the retarding action of the piston 60 ton may be regulated to a nicety.

Surrounding the cylinder 11 and positioned within the chamber 19 is a spiral torsion spring 30. The upper end of this spring is secured to a clutch member 31. 65 This member as shown in detail in Fig. 7

consists of a piece of sheet metal which is stamped into substantially segmental shape and is provided along one edge with a flange 32 and along the opposite edge with a lug 33 and an ear 34. The upper end of the spring passes through the channel provided by the flange 32 and the parts 33 and 34, and extends up through an opening 35 formed adjacent one end of the member. The ear 34 is then bent against the spring 70 to secure the clutch member rigidly to it. The end of the spring which extends through the opening 35 is designated 38 and projects a sufficient distance to be engaged by the finger 13 carried by the spindle. Extending from the inner side wall of the casing is a stop 39 which, upon the movement of the clutch member 31 in one direction, is adapted to be engaged by the lug 33 80 to prevent further rotation of the clutch member 31 in one direction.

The clutch member 25, which is of cast metal, is loosely mounted for rotation upon the sleeve 15' and is provided with two lugs 41 and 42; the lug 41 being arranged above 90 the lug 42 and adapted to engage with a projection 44 extending downwardly from the disk 15. The lug 42 is adapted to engage with a stationary stop 45 projecting upwardly from the bottom of the casing. 95 The bottom coil of the spring 30 is of a reduced diameter and its extreme end is turned upwardly to engage against a shoulder formed by the lug 42 carried by the clutch member 25.

The piston 27 is adapted to be reciprocated by the following construction. Formed in the inner wall of the casing 4 adjacent its upper end, are two cam tracks 46, each extending half way around the casing, as 105 will be clear from Fig. 9. The cover 7 is also provided with similar cam tracks 46' which project downwardly from the cover and are arranged in parallel relation to the tracks 46 providing a cam groove in which 110 is positioned a follower block 47, the outer face of which is curved, as at 48, so as to follow the circular curvature of the inner wall of the groove. This block is substantially triangular in shape as shown in Fig. 115 9, the face 49 thereof, however, being slightly curved and the apex opposite this face being somewhat rounded to permit the block to rock and obtain a relatively long bearing surface as will be referred to in the 120 description of the operation of the device. The follower block 47 is connected to the piston by means of a flat link 50 substantially triangular in shape and having a neck portion 51 upon which the follower block is 125 pivoted. The part 12 of the spindle is provided with a slot 52 in which the flat portion 50 of this link is adapted to ride as the same is reciprocated. This slot does not pass completely through the lower part 130

of the spindle, nor through the part from which the finger 13 projects, and the link is provided with a straight edge 51', which during the upward movement of the link 5 is guided by the wall of the slot.

The operation of the door check and closer is as follows: Assuming that the door is opened in a direction to cause the rotation of the spindle 8 and cylinder 11 in a counter-clockwise direction as viewed in Figs. 2, 4 and 6. The finger 13 engages the end 38 of the spring which projects through the clutch member 31 and rotates the clutch member 31, the lug 33 leaving the stationary stop 39 upon the casing. The lower clutch member 25 remains with the lug 42 in engagement with the stop 45 on the casing, and as the rotation of the spindle is continued, the spring will be placed under tension until 20 the door is fully opened. During this rotation of the spindle, the follower block 47 rides upon one of the cam tracks 46 lifting the link 50 and the piston 27. During this movement, the lifting of the piston since the 25 ball valve 17 is open, permits the free passage of the liquid into the cylinder. When the door is released and is returned to its closed position under the tension of the spring 30, the upper face of block 47 rides 30 upon one of the cam tracks 46' and will force the link 50 together with the piston 27 downwardly. The speed of downward movement of the piston is controlled by the adjustment of the needle valve 22, since the 35 liquid which has entered the cylinder must be exhausted through the restricted orifice 21', since the ball valve 17 is closed. The door therefore returns slowly to its closed position. The liquid or oil after it passes 40 beyond the needle valve 22 flows freely into the casing through the exhaust or outlets 24 and 26. During this downward movement of the piston, the upper face 49 of the follower block exerts a considerable pressure 45 against the cam track 46' and it is for this reason that the face 49 of the follower block is only curved slightly so that a broad bearing is provided which will more effectively resist the wear due to the rubbing contact 50 between this surface and the cam track. During the downward movement of the piston, there is also a tendency for the outer curved face 48 of the follower block to press against the inner wall of the cam groove and it is for this reason that the surface of the 55 follower block is curved to conform to the curvature of this wall so that the follower block will slide more freely thereover and will not become unduly worn by the friction 60 between the parts.

Assuming that the closer and check is attached to a door which is double acting and the spindle 8 is rotated in a clockwise direction as viewed in Figs. 2, 4 and 6, the finger 65 13 which rotates with the spindle then moves

away from the projecting end of the spring 30 and the tension of the spring will hold the lug 33 on the clutch member against the stop 39. The projection 44 on the disk 15 engages the lug 41 upon the clutch member 70 25 to rotate it in a clockwise direction. Since the end of the spring 30 is fastened to the clutch member, the spring will again be placed under tension as the door is opened. The action of the checking device 75 is similar under these conditions.

The liquid used in the chamber 19 is usually one which has lubricating qualities, such as oil, and the link 50 sliding in the slot in the spindle, as well as the bearing 80 for the lower end of the cylinder and other moving parts of the door closer and check, will therefore be thoroughly lubricated so that it is unnecessary to devote any care to the check after it has been once installed. 85

While in the specific embodiment of the invention shown, the cylinder is in axial alignment with the spindle, and the piston is mounted for rotation with the cylinder, yet it is evident that in obvious modifications 90 of the check, the cylinder may be eccentric to the spindle and the piston may be reciprocated without rotating with the spindle and it is my intention that such constructions will come within the scope of the invention where it includes the fundamental feature thereof, namely, a spindle and a depending cylinder secured thereto, whose axis is substantially parallel to the spindle, which parts together form a single operating member. 95 100

If desired the spring which rotates the spindle may be omitted and the device used as a checking mechanism alone either with doors having other means for closing them 105 or with similar members whose movement in one direction should be retarded.

It is evident that the specific construction of the various parts of the device may be modified and the relative arrangement of 110 parts changed without departing from the spirit and scope of the invention. Hence I would have it understood that I do not wish to confine myself to the construction herein shown and described, but only by the scope 115 of the appended claims.

I claim:

1. In a door closer and check, a casing, a spindle, a cylinder mounted for rotation therewith, a piston in said cylinder, resilient 120 means for rotating said spindle and cylinder in one direction, and means for rotating said piston with said cylinder and for reciprocating it when said spindle is rotated.

2. In a door closer and check, a casing, a 125 spindle, a cylinder mounted for rotation therewith, resilient means for rotating said spindle and cylinder in one direction, a piston in said cylinder, a cam track on said casing, and a member rotating with said 130

41
spindle engaging said cam track for reciprocating said piston.

3. In a door closer and check, a substantially cylindrically-shaped casing, a spindle and a cylinder having a closed bottom depending from said spindle, said spindle and cylinder being mounted for rotation in said casing, a cover for said casing, a bearing in said cover for said spindle, a bearing in said casing for the lower end of said cylinder, a spring for rotating said spindle and cylinder, a piston in said cylinder, means for reciprocating said piston upon rotation of said cylinder, and valvular means associated with said piston and cylinder for admitting a fluid to and discharging it from said cylinder upon reciprocation of said piston.

4. In a door closer and check, a substantially cylindrically-shaped casing, a spindle and a cylinder in axial alignment rotatably mounted therein, a cover for said casing, said spindle passing through an opening in said cover, a bearing in said casing for the lower end of said cylinder, a spring for rotating said spindle and cylinder, a cam track in said casing and means rotating with said spindle engaging said cam track for reciprocating said piston.

5. In a door check, a substantially cylindrically-shaped casing, a spindle and a cylinder in axial alignment rotatably mounted therein, a cover for said casing, an annular cam groove on the inner face of said casing formed by substantially parallel cam tracks on said casing and cover, respectively, a part adapted to ride in said cam groove, and means rotating with said spindle for connecting said piston to said part.

6. In a door closer and check, a substantially cylindrically-shaped casing, a spindle and a cylinder in axial alignment rotatably mounted therein, a cover for said casing, said spindle passing through an opening in said cover, a spring for rotating said spindle and cylinder, an annular cam groove in the inner face of said casing and cover, respectively, a follower block adapted to ride in said cam groove, and means rotating with said spindle for connecting said piston to said follower block.

7. In a door check, a casing, a spindle and a cylinder mounted for rotation in said casing, said cylinder having a closed bottom, and a member secured to the bottom of said cylinder for rotatably supporting the lower end of the cylinder, and a bearing on the casing for the upper end of said spindle, said spindle projecting through said bearing.

8. In a door check, a casing, a spindle, a cylinder having a closed bottom secured at its upper end to the lower end of said spindle and in axial alignment therewith, a cylindrical valve body extending into the lower end of said casing, a sleeve mounted on the bottom of said cylinder fitting over said

body, an adjustable needle valve in said valve body having one end thereof projecting exteriorly of the casing, and an orifice controlled by said needle valve affording communication between the cylinder and the valve body, said valve body having other openings therein leading to the chamber formed by the casing.

9. In a door closer and check, a spindle and a cylinder mounted for rotation therein, clutch members in said casing, a spring connected at its ends to said clutch members and stops carried by said spindle, cylinder and casing for causing said spring to be placed under tension irrespective of the direction of rotation of the spindle and cylinder.

10. In a door closer and check, a casing, a spindle mounted in said casing, a spring in said casing, a clutch member comprising an arcuate-shaped piece having an opening therein through which one end of the spring passes, a lug carried by said member, a stop on said casing adapted to co-act therewith, a finger carried by said spindle adapted to co-act with the projecting end of the spring, and means connected with the other end of the spring for holding it under tension.

11. In a door closer and check, a casing, a solid spindle, a cylinder open at one end fitting over the lower end of said spindle and in axial alignment therewith, a piston in said cylinder, an internal cam groove on said casing, a follower block riding in said groove, said spindle having a slot therein, and a link in said slot connecting said block to said piston.

12. A checking mechanism comprising, a casing, a spindle, a cylinder mounted for rotation therewith, a piston in said cylinder, and means for rotating said piston with said cylinder and for reciprocating it when such spindle is rotated.

13. A checking mechanism comprising, a casing, a spindle, a cylinder, mounted for rotation therewith, a piston in said cylinder, a cam track in said casing, and a member rotating with said spindle engaging said cam track for reciprocating said piston.

14. In a door closer and check, a spindle and a cylinder having their axes parallel, a piston in said cylinder, a casing surrounding said cylinder, a spring within said casing surrounding said cylinder for rotating said spindle and cylinder in one direction, means for rotating said cylinder and piston in the other direction, and means for reciprocating said piston upon the rotation of said cylinder and piston.

15. In a checking mechanism, a casing, a spindle in said casing, a cylinder in said casing parallel to said spindle, a piston in said cylinder, a member pivotally connected to said piston, and means for reciprocating said member upon rotation of said spindle.

16. In a checking mechanism, a casing forming a single compartment, a spindle in said casing, resilient means in said casing for rotating said spindle in one direction, a cylinder in said casing, a piston in said cylinder, a member pivotally connected to said piston, and means for reciprocating said member upon rotation of said spindle.
17. In a door check, the combination of a casing, a cylinder therein and a piston in the cylinder, said cylinder and piston being non-rotatable with respect to each other, and means coöperating with the casing for reciprocating the piston upon the rotation thereof.
18. In a door closer and check, a casing, a spindle, a cylinder attached at its upper end to the lower end of the spindle and adapted to rotate therewith, a piston in said cylinder, resilient means for rotating the cylinder and spindle in one direction, and means for reciprocating the piston upon rotation of the cylinder and spindle.
19. A checking mechanism having a casing and comprising a cylinder and a piston therein, and means independent of the cylinder for imparting a reciprocating movement to one of said members with respect to
- the other upon the relative rotation of either of said members with respect to the casing.
20. In a door closer and check, a casing, a spindle and cylinder mounted therein, a spring surrounding said cylinder, a clutch member secured to the upper portion of said spring, a pair of projections associated with said clutch member, a stop carried by said casing adapted to engage one of said projections in one position of said clutch member, a finger carried by said spindle adapted to engage the other of said projections, a second clutch member rotatably mounted in the lower end of said casing, said spring having its other end secured to said clutch member, two lugs on said clutch member, a stop on said casing adapted to engage with one of said lugs, and a projection carried by the cylinder adapted to engage with the other of said lugs whereby upon rotation of the spindle and cylinder in either direction said spring will be placed under tension.

In witness whereof, I subscribe my signature, in the presence of two witnesses.

OSCAR C. RIXSON.
